CLAIM

The ornamental design for a lavatory, as shown and described.

DESCRIPTION

In a preferred embodiment, the nature of this product is as a lavatory suitable for washing hands or the face.

FIG. 1 is a left, top, front perspective view of a lavatory according to my new design;

FIG. 2 is a top plan view thereof;

FIG. 3 is a front elevational view thereof, the rear elevational view thereof being a mirror image of the front view shown;

FIG. 4 is a right side elevational view thereof, the left side elevational view thereof being a mirror image of the right side elevational view shown;

FIG. 5 is a bottom plan view thereof;

FIG. 6 is a sectional view taken along line 6—6 of FIG. 2; and,

FIG. 7 is a sectional view taken along line 7—7 of FIG. 2.
